CLAIM

We claim the ornamental design for an outer surface of a pair of side panels for a dump truck body, as shown and described.

DESCRIPTION

FIG. 1 is a perspective view of the portion of a pair of side panels for a dump truck body showing our new design; FIG. 2 is a side elevational view of the left side panel shown in FIG. 1; FIG. 3 is a side elevational view of the right side panel; FIG. 4 is a top plan view of the left side panel; FIGS. 5 is a bottom plan view of the left side panel; FIG. 6 is a greatly enlarged cross-sectional view of the left side panel as seen from the plane indicated by the line 6—6 in FIG. 2, the right side panel being a mirror image thereof. The broken lines shown are for illustrative purposes only and form no part of the claimed design.
